UNITED STATES PATENT OFFICE.

WALTER EVERETT MENDENHALL, OF MOAB, UTAH, ASSIGNOR TO THE UNION METALS EXTRACTION COMPANY, OF LAKE CITY, COLORADO, A CORPORATION OF COLORADO.

ORE CONCENTRATOR.

Application filed March 23, 1923. Serial No. 627,153.

To all whom it may concern:

Be it known that I, WALTER E. MENDENHALL, a citizen of the United States, residing at Moab, in the county of Grand 5 State of Utah, have invented new and useful Improvements in Ore Concentrators, of which the following is a specification.

The present invention relates to an ore concentrator of the type in which crushed 10 ore or gravel containing precious metals or minerals is passed through a series of oscillating trays and the particles of gold, silver, lead or other minerals separated from the lighter waste particles or tailings and 15 collected in certain depressed portions of the trays.

The general object of the invention is to 20 simplify the construction of this class of devices and at the same time to increase their capacity. In my construction, the check screens which are usually placed between the discharge opening of one tray and the depressed portion of the next lower tray may 25 be dispensed with. The construction of the floor of each tray is such that the same may be rapidly oscillated without loss of the valuable parts of the ore and consequently the capacity of the box is greatly increased.

The structure and principles of my invention 30 will be best understood from the following description taken in connection with the accompanying drawing, which illustrates the preferred embodiment of the invention.

In the drawing:

35 Fig. 1 is a vertical longitudinal section through the tray box.

Fig. 2 is a perspective view of one of the trays.

40 Fig. 3 is a perspective view of the next adjacent tray.

Fig. 4 is a detail sectional view of a modified form of tray.

The ore concentrator, of which my invention forms a part, includes a suitable frame 5 within which a rectangular box 6 is suspended by means of suitable links 7 and 8, connecting the ends of the box to the upper rail of the frame 5 from which the box is suspended. The box is provided with 45 a suitable pitman 9, by means of which it may be oscillated longitudinally of the frame. A series of trays 10 and 11 are suitably supported one above the other within the box 6. Each of the trays is provided 50 with a floor having oppositely-inclined por-

tions 12, with an opening 13 at the upper edge of each inclined portion, through which, as the trays are oscillated, the lighter particles of ore are discharged into the tray next below. It will be noted that the inclined portions 12 of the trays 10 extend upwardly and outwardly toward the end openings 13, while the inclined portions 12 of the trays 11 which alternate with the trays 10, extend upwardly and inwardly toward a central opening 13. Thus, the ore passes back and forth longitudinally of the trays as it passes downwardly through the successive openings 13 and is discharged into the bottom of the box. The floor of each 70 tray has a depressed portion 14 immediately below the opening 13 in the tray next above. This depressed portion is separated from the adjacent lower edge of the inclined portion 12 by a vertical strip or riser 15, which 75 is firmly held in position by a supporting angle bar 16.

The links 7 and 8, by which the box 6 is suspended, extend upwardly from the ends of the box in diverging relation so that 80 as the box is oscillated longitudinally through the medium of the pitman 9, it is also given a longitudinal rocking motion which facilitates the passage of the ore and gravel upwardly along the inclined portions 85 12 of the floors. The box may be oscillated quite rapidly without causing the heavier particles to advance over the floors because of the vertical strips 15. The trays 10 are preferably each provided with a central 90 transverse partition 17 which separates the depressed portion 14 of the floor into two equal parts and assists the initial progress of the ore toward the elevated openings 13 at each end of the tray. 95

In the modification shown in Fig. 4, the floor of the tray 11^a is provided with a depressed portion 14^a, which receives the ore discharged by the tray next above, and the floor between the depressed portion 14^a and 100 the central discharge opening 13^a consists of a succession of upwardly-inclined steps 18 connected by vertical riser strips 19. This modification may, in connection with 105 certain kinds of ore, be found preferable to the form shown in Figs. 1 to 3, since each of the risers 19 performs a function similar to the single riser 15.

It has been found that with a tray constructed in accordance with my invention, 110

the check screen which has been hitherto customarily used between the discharge opening of one tray and the receiving end of the next tray below to prevent cutting the contents of the lower tray may be dispensed with, since the vertical strip 15 will prevent the concentrated portion of the ore from passing onto the upwardly inclined portion 12.

10 In other words, the obstructions formed by the risers aid in effecting a settling of the heavier particles under the influence of the longitudinal parallel oscillation, causing a closer collection of the metallic and mineral substances. They permit a more rapid oscillation, thereby increasing to an important extent the capacity of the trays. They also halt the tendency of the metallic and mineral particles to creep up in the trays 15 when the oscillation is too rapid, thereby neutralizing the adverse effects of a change of speed.

The height of the risers or strips 15 and 19 may be varied to suit the conditions of 20 use and the character of the ore which is treated. It is also to be understood that while I have shown and described specifically the various features of my invention, the same is merely illustrative and various 25 modifications in the proportions of the different parts and their relative arrangements may be made without departing from the scope of the invention as claimed.

What is claimed is:—

30 1. In an ore concentrator, a box mounted for longitudinal oscillation and having a series of trays arranged one above the other, each tray having a floor with an elevated outlet extending transversely across the tray, the floor being inclined downwardly from said outlet and having a level depressed portion connected by a vertical strip 35 with the lower edge of the inclined portion.

40 2. In an ore concentrator, a box mounted for longitudinal oscillation, links by which the box is suspended, means for imparting motion to the box, a series of trays arranged

one above the other within the box, each tray having a floor with an elevated outlet 45 extending transversely across the tray, the floor being inclined downwardly longitudinally from said outlet and having a level depressed portion connected by a vertical strip with the lower edge of the inclined portion, the discharge opening of the floor 50 of one tray being arranged directly above the depressed portion of the floor of the next lower tray.

3. In an ore concentrator, a frame, a box within the frame, upwardly-diverging 55 links connecting the opposite ends of the box to the frame, whereby to impart a longitudinal rocking motion to the box when the latter is oscillated, means for oscillating the box longitudinally, a series of trays 60 arranged one above the other in said box, each tray having a floor with an elevated outlet extending transversely across the same, the outlet of one tray being directly 65 above the lowest portion of the floor of the next tray and the space therebetween being entirely unobstructed.

4. In an ore concentrator, a tray comprising a bottom, having a transversely extending pocket with a level floor, an abrupt rise 70 at the side of the pocket, an inclined portion leading longitudinally upwardly from the abrupt rise, an elevated outlet at the upper edge of said inclined portion, and side walls surrounding and extending above 75 said bottom and said outlet.

5. In an ore concentrator, a box mounted 80 for oscillation and having a series of trays arranged one above the other, each tray having a floor with an elevated outlet, and a 85 depressed level portion, the remainder of the floor including a series of upwardly-inclined steps leading from the depressed portion to the elevated outlet and connected by vertical risers.

In testimony, that I claim the foregoing as my own, I have hereto affixed my signature.

WALTER EVERETT MENDENHALL.
